[57] CLAIM

The ornamental design of a combined music and microphone support stand, substantially as shown and described.

DESCRIPTION

FIG. 1 is a side elevational view of a combined music and microphone support stand showing my design; and FIG. 2 is a perspective view thereof on an enlarged scale with portions broken away for convenience of illustration.

The side of the stand not shown is a mirror image of the side shown in FIG. 1.

The broken line showing of a microphone in FIGS. 1 and 2 is for illustrative purposes only.

FIG. 1
